(57) CLAIM

The ornamental design for a match with a flag attachment, as shown and described.

DESCRIPTION

FIG. 1 is an upper perspective view of the match with a flag attachment showing my design.

FIG. 2 is a front elevation view thereof;

FIG. 3 is a back elevation view thereof;

FIG. 4 is a side elevation view thereof;

FIG. 5 is an opposite side elevation view thereof;

FIG. 6 is a top plan view thereof;

FIG. 7 is a bottom plan view thereof; and,

FIG. 8 is another upper perspective view thereof, showing placement in a stand in broken lines.

The features shown in broken lines are presented for illustrative purposes and form no part of the claimed design.
